(57) **CLAIM**

The ornamental design for an automated analyzer, as shown
and described.

DESCRIPTION

FIG. 1 is a left-side perspective view of a first embodiment of the automated analyzer showing our new design.
FIG. 2 is a right-side perspective view thereof.
FIG. 3 is a front view thereof.
FIG. 4 is a back view thereof.
FIG. 5 is a top view thereof.
FIG. 6 is a bottom view thereof.
FIG. 7 is a left-side view thereof.
FIG. 8 is a right-side view thereof.
FIG. 9 is a left-side perspective view with the sample analyzing section's covers open.
FIG. 10 is a right-side perspective view with the sample analyzing section's covers open.
FIG. 11 is a reference view showing the sections of the automated analyzer.
FIG. 12 is a left-side perspective view of second embodiment of the analyzer showing our new design.
FIG. 13 is a right-side perspective view thereof.
FIG. 14 is a front view thereof.
FIG. 15 is a back view thereof.
FIG. 16 is a top view thereof.
FIG. 17 is a bottom view thereof.
FIG. 18 is a left-side view thereof.
FIG. 19 is a right-side view thereof.
FIG. 20 is a left-side perspective view with the sample analyzing section's covers open.
FIG. 21 is a right-side perspective view with the sample analyzing section's covers open.
FIG. 22 is a reference view showing the sections of the automated analyzer.
FIG. 23 is a left-side perspective view of a third embodiment of the automated analyzer showing our new design.
FIG. 24 is a right-side perspective view thereof.
FIG. 25 is a front view thereof.
FIG. 26 is a back view thereof.
FIG. 27 is a top view thereof.
FIG. 28 is a bottom view thereof.
FIG. 29 is a left-side view thereof.
FIG. 30 is a right-side view thereof.
FIG. 31 is a left-side perspective view with the sample analyzing section's covers open.
FIG. 32 is a right-side perspective view with the sample analyzing section's covers open; and,
FIG. 33 is a reference view showing the sections of the automated analyzer.
